CLAIM

The ornamental design for a side vent for automobile or replica thereof, as shown and described.

DESCRIPTION

FIG. 1 is a front, left perspective view of a side vent for automobile or replica thereof in accordance with the present design;

FIG. 2 is a rear, left perspective view of FIG. 1;

FIG. 3 is a left elevation view of FIG. 1;

FIG. 4 is a right elevation view of FIG. 1; and,

FIG. 5 is a top plan view of FIG. 1.

The dot-dash lines depict a boundary between claimed portions, which are inside the dot-dash lines, and portions that are not claimed, which are outside the dot-dash lines, of the side vent for automobile replica thereof. Portions of the side vent for automobile or replica thereof shown in evenly spaced broken lines depict environmental structures that form no part of the claim.
